(57) **CLAIM**

The ornamental design for a multi-function imaging and printing device, substantially as shown and described.

DESCRIPTION

FIG. 1 is a left-front perspective view of the multi-function imaging and printing device showing the top and front panels in a closed position;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another left-front perspective view thereof showing the top and front panels in an open position.

The portions shown in broken lines are for illustrative purposes only and form no part of the claimed design.
